UNITED STATES PATENT OFFICE

93,373

DESIGN FOR A VENDING MACHINE CASING

Edward L. Zacher, South Bend, Ind.

Application July 6, 1934, Serial No. 52,472

Term of patent 14 years

To all whom it may concern:

Be it known that I, EDWARD L. ZACHER, a citizen of the United States, residing at South Bend, in the county of St. Joseph, State of Indiana, have invented a new, original, and ornamental Design for a Vending Machine Casing, of which the following is a specification, reference being had to the accompanying drawing forming a part hereof.

Figure 1 is a perspective view of the vending machine casing.

Figure 2 is a view of the vending machine casing in front elevation.

Figure 3 is a view of the vending machine casing in end elevation.

I claim:

The ornamental design for a vending machine casing as shown.

EDWARD L. ZACHER.
